UNITED STATES PATENT OFFICE.

HARRY J. L. FRANK AND LEON H. FRANK, OF DETROIT, MICHIGAN, ASSIGNORS TO MUTUAL ELECTRIC & MACHINE COMPANY, OF DETROIT, MICHIGAN, A CORPORATION OF MICHIGAN.

STARTING-SWITCH FOR MOTORS.

1,338,825.

Specification of Letters Patent.

Patented May 4, 1920.

Application filed September 18, 1916, Serial No. 120,843. Renewed March 24, 1920. Serial No. 368,317.

To all whom it may concern:

Be it known that we, HARRY J. L. FRANK and LEON H. FRANK, both citizens of the United States of America, residing at Detroit, in the county of Wayne and State of Michigan, have invented certain new and useful Improvements in Starting-Switches for Motors, of which the following is a specification, reference being had therein to the accompanying drawings.

The invention relates to starting switches for motors and it is the object of the invention to obtain an improved construction in which the motor circuits are closed through fuses when the motor is normally running and closed through circuits around the fuses when the motor is starting; in which it is impossible to start the motor without having the fuses short circuited during the initial rush of current; and in which the whole act of starting up to and including the running position is accomplished without opening the circuit at any time. It is another object of the invention to obtain a construction which is simple, compact and durable and at the same time is easily accessible for renewal or repair of the parts; and further to obtain various advantages hereinafter set forth.

In the drawings:

Figure 1 is a perspective view of the switch casing showing the trip mechanism for the switch;

Fig. 2 is a perspective view of the improved switch with its trip mechanism;

Fig. 3 is a cross-section through the main and auxiliary switch blades in engagement with their contacts;

Fig. 4 is a side elevation of the switch casing showing a modified construction of the trip mechanism.

A is the crank handle for operating the switch. B is a shaft having a crank B' therein for engaging the switch blades C, C' and C² of a knife switch. Each of these blades is composed of two separate members D and E, the former being the main switch blade and arranged centrally, while the latter is the auxiliary switch blade and is of inverted U-shaped cross section embracing the blade D. Both blade members D and E are pivoted to a common center F and the corresponding blade members of the several

blades C, C' and C² are connected by insulator bars G' and G, respectively.

55

The crank B is mechanically connected to the insulator bar G by eye-bolts H and the arrangement is such that in rocking the crank handle A to close the switch, both blade members D and E will be moved, the former engaging contacts J and J' and the latter engaging contacts I and I'. Further the arrangement is such that the blade member E engages its contacts I and I' before or at least simultaneously as it forces 65 the blade member D into engagement with its contacts J and J'. The contacts J and J' are connected into circuit through a fuse K while the contacts I and I' are connected into circuit through a bar L which short 70 circuits the fuse K. The switch contact to which the separate blade members are pivoted is connected to the line contact F' while the switch contacts I and I' and J and J' through the bar L and fuse K respectively are connected to the line contacts F².

75

Thus, in operation, when the switch is closed the blade members E will first contact with the contacts I and I' and close 80 the shunt circuit about the fuse K so as to relieve the latter from the starting load and prevent blowing of the fuse. The switch will remain in this condition as long only as the handle A is manually held down, 85 the spring M secured to the casing A' which incloses the switch, engaging the crank B' and tending to open the switch. As soon as the handle A is released the spring M will rock the shaft B and its crank B' in 90 the reverse direction, thereby opening the circuit closed by the member E and continuing the circuit through the blade members D which are in series with the fuse K. Guards R secured to the member E 95 prevent arcing of the electric current.

100

Return movement of the shaft B is arrested by a catch member N rotatably mounted thereon, which engages a detent O pivoted upon a side of the casing A', 105 and which may be tripped by a handle P depending from the detent O and extending below the casing A' sufficiently to be grasped, a coil spring S secured to the casing and detent normally maintaining said 105 detent in position to engage the catch mem-

ber. The catch member N is provided with a projection O' for engaging the detent O and with projections O² extending into the path of the handle A for engaging the same, the projections O² being spaced a sufficient distance from each other to permit of relative movement of the handle A and the catch member N. Lost motion linkage Q permits the return of the shaft B with its 10 crank B' until arrested by the catch member N without moving the switch blades D, said lost motion linkage Q consisting of a rod secured at one end to the blades D and flanged at the other end to engage the 15 blades E upon sufficient movement thereof. When the trip is operated the shaft B will return to its original position and through the medium of the lost motion linkage Q the blades D will be opened from their 20 contact members J and J'.

In the modified construction of trip mechanism as shown in Fig. 4 the catch member N² is fixedly mounted upon the rock shaft B² and the handle A² is rotatably mounted 25 thereon. The catch member N² is cam shaped and provided with a projection O⁴ for engaging the detent O³ pivoted on the casing A³, and the handle A² is provided with a lug T on its inner face, the arrangement being such that the lug T engages the 30 catch member in one direction of rotation of the handle to rotate the catch member and the rock shaft upon which the catch member is fixedly mounted and in the opposite direction of rotation the detent to 35 disengage the same from the catch member thereby releasing the switch blades. The spring S' normally maintains the detent O³ in engagement with the catch member.

40 What we claim as our invention is:

1. A switch, comprising two-part blades, the operation of one of said blades being dependent upon the other, means for manually actuating said other blade in one direction of rotation, yieldable means for actuating said other blade in the reverse direction, means for maintaining said dependently operated blade in the position adjusted by said other blade in its first mentioned direction 45 of rotation, means for limiting the movement of said other blade in the reverse direction, and means for actuating said limiting means to permit further movement of said other blade in said reverse direction.

50 2. A switch, comprising two-part blades, the movement of one of said blades being dependent upon the other blade, a shaft having a crank for operating said other blade, trip mechanism permitting movement of said shaft in one direction to close said other blade and its dependently moving blade and limiting movement thereof in the opposite direction, and means for actuating said trip mechanism.

3. In a switch, the combination with separate blades, of a rock shaft for operating said blades, means for actuating said rock shaft, a catch member provided with spaced projections in the path of movement of said rock shaft actuating means, and a movable 70 detent for engaging said catch member.

4. In a switch, the combination with separate blades, of a rock shaft for actuating said blades, means for actuating the same, a catch member having a pair of spaced projections in the path of movement of said actuating means permitting of relative movement thereof, and a separate projection, a pivoted detent for engaging said separate projection, and a handle for actuating said pivoted detent to trip said catch member.

5. In a switch, two-part blades, one of said blades contacting with and actuating the other of said blades in one direction of movement, a lost motion connection between said blades for actuating said second mentioned blade from the first mentioned blade, a rock shaft for operating said first mentioned blade, and a catch member limiting 90 the return movement of said rock shaft to prevent actuating engagement of said first mentioned blade, and said member secured to the other blade, and means for tripping said catch member.

6. A switch, comprising two-part blades, a rock shaft for operating said blades, trip mechanism permitting movement of said shaft in one direction to close said blades and limiting movement thereof in the opposite direction to permit the opening of one blade, the other remaining closed, and means for actuating said trip mechanism.

7. In a switch, the combination with separate blades, of a rock shaft for operating 105 the same, a handle secured to said rock shaft for actuating the same, a catch member rotatably mounted on said rock shaft adapted to contact with said handle to permit of relative rotation, and a movable detent for engaging said catch member.

8. In a switch, the combination with separate blades, of a rock-shaft for operating the same, relatively movable catch and handle members upon said rock shaft adapted to engage each other, one of said members being secured to said rock-shaft, and a detent for engaging said catch member.

9. In a switch, the combination with separate blades, of a rock-shaft for operating the same, relatively movable members upon said rock shaft, one of said members being secured thereto, means for engaging and retaining said last mentioned member in a 120 predetermined position, and means for actuating said last mentioned member through the other into said predetermined position 125

and for releasing said engaging and retaining means therefrom.

10. A switch comprising two blades, the movement of one of said blades being dependent upon the other, means for operating said other blade, trip mechanism permitting movement of said operating means in one direction to close said other blade and its dependently moving blade and limiting movement thereof in the oposite direction, and means for actuating said trip mechanism.

11. In a switch, the combination with a line contact of main and auxiliary blades connected to said line contact, a second line contact, main and auxiliary blade contacts insulated from each other and adapted to be engaged respectively by said main and auxiliary blades, a fuse connecting said second line contact with said main switch contact, an electrical connection between said second line contact and said auxiliary switch contact, and means for actuating one of said blades, the operation of said other

blade being dependent upon the actuated blade.

12. A switch, comprising two part blades, the movement of one of said blades being dependent upon the other, means for actuating said other blade in one direction of movement, means for actuating said other blade in the reverse direction, means for maintaining said dependently operated blade in the position adjusted by said other blade in its first - mentioned direction of movement, means for limiting the movement of said other blade in the reverse direction, means for actuating said limiting means to permit further movement of said other blade in said reverse direction, and a connection between said blades for moving said dependently operated blade in said reverse direction.

In testimony whereof we affix our signatures.

HARRY J. L. FRANK.
